UNITED STATES PATENT OFFICE

CLIFFORD M. CRANE, OF ST. PAUL, MINNESOTA, ASSIGNOR TO LUCIUS WINCHESTER,
OF CHICAGO, ILLINOIS

POSITIVE WATER CIRCULATOR

Application filed April 10, 1926, Serial No. 101,120. Renewed April 27, 1931.

This invention relates to a boiler, and particularly to a water circulating means for a boiler. While the invention is applicable to various types of boilers, it particularly is designed for use with a locomotive boiler to form a positive water circulator.

In most boilers and in locomotive boilers, there is usually a space at the front and lower portion of the boiler where there is little or no circulation of water. This dead water space as it is called, has several very serious objections. The flues at this portion of the boiler become pitted and corroded and frequent replacement of the flues at this portion is necessary. The non-circulation of the water also causes unequal heating of the water and this causes unequal expansion and contraction of the flue sheets, thus tending to loosen the flues and damage the sheets. The front flue sheet for this reason is usually made of thicker material than the rear sheet. The unequal circulation of the water also results in an inefficient use of the heat generated and thus an inefficient use of the fuel consumed. The non-circulation also results in an objectionable deposit of sediment at the front and lower portion of the boiler.

It is an object of this invention to provide a simple and efficient means for causing a circulation of the water at the front and lower portions of the boiler, resulting in an equal and efficient heating of the boiler water.

It is a further object of the invention to provide a positive water circulation including means extending into the hot end chamber at the front of the boiler by means of which the water is evenly and effectively circulated at all portions of the boiler.

It is more specifically an object of the invention to provide a circulating means for a locomotive boiler comprising one or more open ended pipes connected to the front flue sheet at the lower portion thereof, extending forwardly into the hot end chamber around the space above the exhaust nozzle and then rearwardly and upwardly to the upper portion of said flue sheet adjacent the water line of the boiler. Preferably, a conduit or conduits are also provided leading from the feed pipe and boiler check to adjacent the

lower end of said pipes and a conduit leading from the upper end of said pipes to a point adjacent the rear end of the boiler, and having its end directed downwardly.

These and other objects and advantages of the invention will be fully set forth in the following description made in connection with the accompanying drawings, in which like reference characters refer to similar parts throughout the several views and in which:—

Fig. 1 is a vertical section through a front portion of a locomotive, showing the invention applied thereto;

Fig. 2 is a vertical section taken on line 2—2 of Fig. 1 as indicated by the arrows;

Fig. 3 is a horizontal section taken on line 3—3 of Fig. 1 as indicated by the arrows; and

Fig. 4 is a vertical section of the rear end portion of a locomotive boiler, showing the invention therein, Fig. 4 being shown on a reduced scale.

Referring to the drawings, a portion of a locomotive or locomotive boiler is shown comprising the boiler shell 6 having secured therein the usual front flue sheet 7 in which are secured the front ends of the fire flues 8. The chamber at the front of the flue sheet 7 is shown, which is usually called the hot end chamber, and comprises the shell 9 having the vertical partition 10 therein with the damper 11 shown adjacent the bottom thereof and in the horizontal shelf or partition 12. A screen partition 13 extends upwardly from the forward end of the shelf 12 to a point adjacent the front end of the shell 9 and said shell 9 has the usual closing plate 14 at its front end. The exhaust nozzle 15 is shown extending from the bottom of the shell 9 upwardly through the shelf 12, and vertically aligned with and spaced above said exhaust nozzle is the stack 16. The parts so far described form a customary standard structure of the modern locomotive. A super-heating unit (not shown) is often disposed between the flue sheet 7 and the partition 10.

In accordance with the present invention, one or more conduits or pipes 17 are pro-

vided. While these pipes may be variously formed, in the embodiment of the invention illustrated, they are shown as cylindrical. Two of the conduits 17 are shown and the same extend from the lower side portion of the flue sheet 7 and have their open ends secured therein. While these ends may be variously secured, they are preferably provided with flanges 17a having a beveled portion extending through the flue sheet 7 and adapted to extend into and be bolted to a flange 18 on the opposite side of said flue sheet, the engaging portions of flanges 17a and members 18 being formed as a ground joint. The pipe 17 can thus be readily and easily removed by merely removing the bolts connecting the same and members 18. The conduits 17 extend forwardly from their lower ends and the flue sheet 7 around the exhaust nozzle 15, then upwardly through the partition 13 at each side of the stack 16 and rearwardly through the space between partition 10 and sheet 7 to said sheet 7, where they have their upper ends also provided with flanges 17a attached to the members 18 at the inner side of the flue sheet. It will be noted that each conduit 17 extends across the shell 9 and has its upper end secured at the opposite side of the flue sheet 7 from its lower end, so that said conduits cross each other. In the modern practice the feed water is led into the boiler through a pipe 19, said pipe extending into the boiler and having a discharge or nozzle section 19a adjacent which is disposed in the pipe a check valve, commonly known as the boiler check. In the present invention a conduit 20 is provided for each conduit 17 and a pipe 19 leads to each of the conduits 20 and the nozzle 19a of pipe 19 is alined with and slightly spaced from the front open end of the conduit or pipe 20 as shown in Figures 1 and 3, the end of pipe 20 being shown as somewhat flared. Each pipe 20 extends forwardly and downwardly and has its lower open end disposed in alinement with and spaced a few inches in front of the open end of the pipe 17. Pipes 20 will be suitably supported from shell 9 by means not shown. A pipe or conduit 21 is also provided at each side of the boiler suitably supported by means not shown from shell 9, the forward end of which is alined with and spaced some distance from the upper open end of respective pipe 17. The pipes 21 lead to the rear of the boiler adjacent the water line and preferably have their rear ends 21a directed downwardly adjacent the front of the rear flue sheet 7a and at substantially the point where the water legs 6a are formed, adjacent the rear flue sheet.

In operation, water will be delivered through the boiler and will occupy a level therein indicated at 22. The water will be forced into the boiler in the usual way through the pipes 19 and will be discharged

through the nozzles 19a. A large part of this water will be directed into the pipes 20 and a circulation thus induced in said pipes. The water will pass downwardly and forwardly through the pipes 20 and be directed forwardly in alinement with the conduit 17. A circulation will thus be induced or produced by the feed water in the pipes 17. The hot gases from the furnace pass through the flues 8 into the space between flue sheet 7 and partition 10 and downwardly through the opening afforded by damper 11 below the shelf 12. The gases then pass upwardly through the screen partition 13 and are carried out through the stack 16. As is well known, a strong draft is produced in the locomotive and stack by the exhaust steam in the cylinders being discharged through the exhaust nozzle 15 and upwardly into the stack 16. The flue gases are drawn by this draft into the stack and ejected therethrough. The conduits 17, it will be noted, are disposed in the path of the flue gases and will be highly heated thereby. The water in the pipes 17 will thus be heated and this will additionally tend to produce a circulation of water upwardly in the pipes 17. This, together with the circulation induced by the water discharged from pipes 20 will cause a strong and positive circulation through these pipes 17, so that the water will be discharged rearwardly from the pipes 17 at the upper portion of the flue sheet and adjacent the water line in the boiler. This water being directed rearwardly, will in large part pass into the conduits 21 and therethrough and be delivered at the rear portion of the boiler and directed downwardly therein by the ends 21a of the pipes 21. As the water is discharged from pipes 20 into the conduits 17, a circulation will also be induced into the pipes 17 from the water surrounding the pipes 20, so that the water at the lower front end of the boiler will be drawn into the pipes 17, which pipes are larger in diameter than the pipes 20. As the water is discharged from the top of pipes 17, a circulation of the water at the top of the boiler in a rearward direction will be produced so that the water will continually move away from the pipes 17. Not only, therefore, is a circulation produced through pipes 20, 17 and 21, but an additional circulation is produced in the boiler, forwardly at the bottom portion thereof through the pipes 17 and rearwardly at the top portion of the boiler. The entire water of the boiler is thus kept in positive and continuous circulation.

With the use of the described apparatus, the dead water space at the front lower end of the boiler is eliminated. The undue deposit of sediment is also prevented and the injurious action on the plates and flues due to the non-circulation of water and the deposit of sediment is prevented. The con-

tinuous and positive circulation of the water in the boiler results in an even heating of the water and unequal stresses due to uneven heating are eliminated, thus adding to the 5 life or durability of the boiler. The water being evenly heated, the heat generated in the furnace is more efficiently used and a greater amount of steam will be generated for a unit of fuel. This really means a saving in 10 the fuel used. A large portion of the feed water delivered into the boiler, instead of being spread, as usual, directly toward or over the crown sheet at the rear of the boiler, is first preheated and passed through the 15 pipes 17 and is delivered to the rear portion of the boiler at a higher temperature. This also eliminates the objectionable differences of temperature between the feed water and the water in the boiler.

20 It will be noted that the pipes 17 can be readily removed from the front end of the boiler or locomotive, which end is always provided with doors. The pipes 17, as stated, are secured by ground joints fitted into the 25 front flue sheet and can thus be readily detached so as to be replaced or cleaned. The pipes 17 are quite large in diameter, so that there will be no possibility of the same being quickly filled up with sediment or precipitates from the water.

30 With the present invention the front flue sheet can be made of as light a material as the rear sheet and as above stated, the damage and necessary replacement of the flues at the lower front portion 35 of the boiler will be eliminated.

From the above description it is seen that applicant has provided a simple and efficient means for causing an effective circulation in the boiler and particularly a locomotive boiler, and one which will have a high degree of utility and one constituting a decided improvement and advance in the art. The invention is simple and can be readily installed in boilers or locomotives already in use, or 45 also easily installed in new boilers or locomotives.

It will, of course, be understood that various changes may be made in the form, details, arrangement and proportions of the 50 parts, without departing from the scope of applicant's invention, which, generally stated, consists in a device capable of carrying out the objects above set forth, in the novel parts and combinations of parts disclosed and defined in the appended claims.

What is claimed is:

1. A water circulating means for a boiler, having a front flue sheet and a hot gas chamber at the front of the same, comprising one or more open ended conduits extending from the lower front portion of the boiler and flue sheet forwardly into said chamber then upwardly and rearwardly to the flue sheet and boiler adjacent the water level thereof, and a conduit in the lower portion of said boiler

for each of said first mentioned conduits, each of said last mentioned conduits having its front end spaced a short distance from and substantially alined with the lower end of its respective first mentioned conduit and means for directing water through said last mentioned conduits to assist the heat in said gas chamber in causing a circulation of water from the lower portion of the boiler to the top thereof.

2. A water circulating means for a boiler, having a front flue sheet and a hot gas chamber at the front of the same, comprising one or more open ended conduits extending from the lower front portion of the boiler and flue sheet forwardly into said chamber, then upwardly and rearwardly to the flue sheet and boiler adjacent the water level thereof, a pipe in said boiler for each of said conduits having its lower front portion spaced from and substantially alined with the lower portion of its respective conduit, means for directing water through each pipe and a pipe in the upper portion of said boiler for each of said conduits, having its front end spaced from and alined with the front end of its respective conduit and extending to the rear end of the upper portion of said boiler, whereby the heat of said gas chamber on said conduits and the water directed through said first mentioned pipes will cooperate to create a continuous circulation of water between the bottom and top of said boiler.

3. A water circulating means for a boiler having a front flue sheet and a hot gas chamber at the front of said sheet comprising conduits having their lower ends respectively secured in said sheet at the lower portion thereof and communicating with the boiler, said conduits extending forwardly into said chamber and upward therein, and having their upper ends secured in said flue sheet adjacent the water line of the boiler, and means spaced from and disposed adjacent the lower ends of said conduits for directing water thereinto and cooperating with the heat of said gas chamber to induce a circulation from the bottom to the top of the boiler through said conduits.

4. The structure set forth in claim 3, said last mentioned means comprising a pipe for each of said conduits, having its lower end spaced from and substantially alined with the lower end of its respective conduit and extending upwardly and rearwardly in said boiler and a feed water pipe having its discharge end spaced from and substantially alined with the rear end of said pipe.

5. The structure set forth in claim 3, said last mentioned means comprising a pipe for each of said conduits, having its lower end spaced from and substantially alined with the lower end of its respective conduit and extending upwardly and rearwardly in said boiler, a feed water pipe having its discharge

end spaced from and substantially alined boiler spaced from the opposite end of said with the rear end of said pipe, and a conduit at the top of the boiler for each of said first mentioned conduits having its front end 5 spaced from and substantially alined with the upper end of its respective conduit, extending to the rear end of the boiler and having its rear end directed downwardly.

6. The combination with a locomotive 10 boiler having a front flue sheet, a hot gas chamber at the front thereof, an exhaust nozzle extending upwardly in said chamber and a stack spaced above and alined with said exhaust nozzle of a pair of conduits 15 having their lower open ends extending from said boiler and flue sheet, forwardly into said hot gas chamber at each side of said exhaust nozzle, upwardly and laterally and then rearwardly at the side of said stack and 20 to the upper portion of said flue sheet and disposed at the opposite side portion thereof from their lower ends, a pipe for each of said conduits having its front end substantially alined with and spaced from the lower end 25 of its respective conduit and extending upwardly and rearwardly, a feed water pipe for each of said latter pipes extending into the boiler and having a discharge end substantially alined with and spaced from the 30 rear end of its respective pipe, and a conduit for each of said conduits in said boiler having a forward end spaced from and substantially alined with the upper end of its respective conduit and extending rearwardly 35 in the boiler to a point adjacent the crown sheet.

7. A water circulating means for a boiler comprising an upwardly extending conduit secured at one end to the front sheet of said 40 boiler and communicating with the lower front portion of the boiler and secured at its other end to said front sheet and communicating at said latter end with the upper portion of the boiler adjacent the water line 45 thereof, a conduit in the lower portion of the boiler alined with and spaced a short distance from the lower end of said first mentioned conduit and means spaced from said last mentioned conduit for supplying water 50 toward and through the same to force a certain amount of the supplied water and a certain amount of the water in the bottom of said boiler to the top thereof and thus create a circulation of the water in the boiler.

8. In combination with a boiler having a flue sheet and a hot gas chamber at the outer side thereof, of a conduit secured at one end in said flue sheet at the lower portion of the 60 boiler extending into said hot gas chamber, reversely bent and secured at its other end in said flue sheet adjacent the water line of said boiler, a tube in said boiler having one end spaced from said first mentioned end of said 65 conduit, and water feeding means in said

In testimony whereof I affix my signature.
